United States Patent Office.

GEORGE ENGLE, OF PATCH GROVE, WISCONSIN.

Letters Patent No. 92,177, dated July 6, 1869.

IMPROVEMENT IN LUMBER-SLEDS.

The Schedule referred to in these Letters Patent and making part of the same.

To whom it may concern:

Be it known that I, GEORGE ENGLE, of Patch Grove, in the county of Grant, and State of Wisconsin, have invented a new and useful Improvement in Lumber-Sleds; and I do declare that the following is a true and accurate description thereof, reference being had to the accompanying drawings, in which—

Figure 1 is a side elevation.

Figure 2 is a plan view.

Figure 3 is a back elevation of the front sled.

Figure 4 is a rear elevation of the back sled.

Letters of like kind denote like parts in each figure.

This device belongs to the class of double sleds intended for use in drawing saw-logs, timber, and long lumber of all sorts over rough roads, and is so constructed as to have more flexibility than those in common use. It is found upon trial, in newly-settled and timbered countries, where, by necessity, the roads in use can be made only by cutting away the trees, without any attempt at grading the earth, that sleds made in the usual way, loaded with saw-logs, fence-poles, trees, or other long lumber, are constantly strained apart and broken down by the irregularities of the surface over which the load is drawn, as well as by the frequent and short turns made necessary in such rude roads.

This device is designed to have such flexibility of movement in every direction, and in every part of its construction, as to avoid the rigidity which has proved so injurious to sleds of ordinary form.

A is the front sled, and B is the back sled, made in the usual form, with runners C C', rails D D', and standards E E' E' E", except that in each pair of standards in each sled, one is turned into the runner, a little back of the other, and with roller F, made in the usual manner, to which the tongue is attached.

G and G' are the rockers, and

H is the reach connecting the sleds.

K K' K' K" are the cross-bars, square at one end and round at the other.

The front rocker G traverses on rocker-bar I, by means of a bolt, which passes through the centre of said rocker and the front end of the reach H, which is tenoned into said rocker, and through the rocker-bar I, which, in turn, is pivoted at each end to the square ends of the cross-bars K K', by means of two pairs of staples, two of which are in said rocker-bar I, and two in said cross-bars K K'.

To the cross-bars K K' K' K", at their square ends, the standards E E' E" are tenoned, and their round ends play in staples L L' L' L" on the under side of the rail D D', and attached to it in such a manner, that in each pair of cross-bars to each sled, one end of each is rigidly attached to a standard, and one end plays in said staple; and the two bars being side by side, the

rigid end of one and the playing end of the other come together.

The rear rocker G' is pivoted to the rear cross-bars K' K", in the same manner as the front rocker G to the rocker-bar I.

The reach H is square where it is tenoned into the front rocker G, and round the remainder of its length. It extends from said front rocker backward, under the centre of the back rocker G', and over the back cross-bars K' K", and behind the sled a sufficient distance. It plays back and forth under the back rocker, between two longitudinal guides, M M, which are halved into the under side of said rocker G', and fastened to it, and extending forward each side of the reach, are secured to their front ends, by bolts passing down through a covering-board, N, and through said guides into a cross-brace on the under side of said guides.

On the front end of said reach H, and near the front rocker G, is a metallic swivel, O, which traverses loosely on said pole, and forms ears on each side of it.

A rod, P, connects it with the front of each runner of the back sled.

Behind this swivel is a linchpin, passing through said reach, which prevents it from drawing out, and by means of various holes in it, regulates the distance between the sleds.

In the ends of the rockers are holes for stakes, in the usual way.

In operation, and loaded with long lumber of any sort, this double sled has, by means of its peculiar construction of rockers, cross-bars, and reach, a flexibility, not only of each sled as toward the other, but an independent flexibility, and in addition, an independent flexibility of each runner.

It is simple of construction, so that it can be made by any farmer or woodsman, is cheap, easy of repair, and effective in its work.

What I claim as my invention, and desire to secure by Letters Patent, is—

The construction and arrangement of the cross-bars K K' K" K", playing in staples L L' L' L", so as to secure an independent flexibility of each runner, as and for the purpose set forth above.

Also, the combination and arrangement of the rockers G G', rocker-bar I, cross bars K K' K" K", reach H, swivel O, with its rod P and linchpin, and rails D D', in connection with sleds A and B, when constructed and operating substantially as and for the purpose described.

GEORGE ENGLE.
